UNITED STATES PATENT OFFICE.

AUGUST V. LAMBERT, OF NEW YORK, N. Y., ASSIGNOR TO LAMBERT BROS., OF NEW YORK, N. Y., A FIRM.

DESIGN FOR A BRACELET.

No. 38,381.

Specification for Design.

Patented Dec. 25, 1906.

Application filed November 19, 1906. Serial No. 344,161. Term of patent 3½ years.

To all whom it may concern:

Be it known that I, AUGUST V. LAMBERT, a citizen of the United States, residing at the borough of Manhattan, in the city, county, and State of New York, have invented a new, original, and ornamental Design for Bracelets, of which the following is a specification, reference being had to the accompanying drawing, forming part thereof.

The figure is an elevation of a bracelet showing my new design.

I claim—

The ornamental design for a bracelet, as shown.

AUGUST V. LAMBERT.
